INVENTOR.
BY J. H. Bonar

Victor J. Evans
ATTORNEY.

UNITED STATES PATENT OFFICE.

JAMES H. BONAR, OF NEW LONDON, IOWA.

OIL-CAN.

1,368,104.

Specification of Letters Patent.

Patented Feb. 8, 1921.

Application filed December 2, 1919. Serial No. 341,920.

To all whom it may concern:

Be it known that I, JAMES H. BONAR, a citizen of the United States, residing at New London, in the county of Henry and State of Iowa, have invented new and useful Improvements in Oil-Cans, of which the following is a specification.

This invention relates to improvements in oil cans and the principal object of the invention is to provide the can with a pump for forcing the oil therefrom.

Another object of the invention is to so form the pump that valves are rendered unnecessary and thus the danger of clogging the device is obviated.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a sectional view of my improved can.

Fig. 2 is a view of the pump removed from the can.

In these views 1 indicates the can which is provided with the spout 2 and with the filling spout 3. The can is also provided with the handle 4 and with the chamber hole 5 on the top thereof. The pump cylinder 6 is inclinedly arranged in the can with its upper end projecting from the top thereof and its other end resting on the bottom.

Substantially semicircular shields 7 are connected with the lower part of the cylinder at opposite sides thereof, the upper ends of these shields being closed and the lower ends opened. These lower ends are provided

with projections 7' for preventing the openings from being closed by the bottom of the can. Inlet holes 8 are formed in the cylinder within said shields to permit the oil in the shields to pass into the cylinder. An outlet pipe 9 is connected with the bottom of the cylinder between the shields and this pipe extends upwardly and into the spout 2

of the can. A piston 10 is located in the cylinder with its rod 11 passing through the upper end of the same with its outer end provided with the handle 12. A spring 13 on said rod tends to hold the piston in raised position. Outlet holes 14 are arranged in the upper part of the cylinder for the escape of oil.

It will thus be seen that the oil in the can will pass through the opened bottoms of the shields into the spaces between the shields and cylinder and from these spaces the oil will pass through the holes 8 into the cylinder. By pressing upon the handle 12 of the piston rod the piston will be forced downwardly, thus forcing the oil within the cylinder through the pipe 9 and ejecting it from the end of the spout 2. As soon as the hand is removed from the handle 12 the spring 13 will return the piston to its upper position and this upward movement will draw oil into the cylinder again.

It will be seen that no valves are used as I find that valves tend to clog and stick and thus prevent the oil from being ejected.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A valveless pump for oil cans comprising a cylinder having inlet holes therein adjacent its lower end, a shield connected with the cylinder and surrounding said holes, said shield having its lower end open, an outlet pipe connected with the bottom of the cylinder below the openings, a piston in said cylinder and a piston rod connected therewith.

2. In combination with an oil can and its spout, a pump in the can, an outlet pipe connected with the bottom of the pump and projecting into the spout, said pump having inlet holes therein and shields inclosing said inlet holes and having their lower ends open.

In testimony whereof I affix my signature.

JAMES H. BONAR.
